UNITED STATES PATENT OFFICE.

WILLIAM C. LAECHLER, OF CHICAGO, ILLINOIS.

BURIAL-VAULT.

No. 877,095.

Specification of Letters Patent.

Patented Jan. 21, 1908.

Application filed May 23, 1907 Serial No. 875,294.

To all whom it may concern:

Be it known that I, WILLIAM C. LAECHLER, a citizen of the United States, and a resident of the city of Chicago, in the county of Cook 5 and State of Illinois, have invented certain new and useful Improvements in Burial-Vaults; and I do hereby declare that the following is a full, clear, and exact description of the same, reference being had to the accompanying drawings, and to the letters 10 of reference marked thereon, which form a part of this specification.

This invention relates to improvements in burial vaults, more particularly in a burial 15 vault constructed of armored concrete.

The object of this invention is to provide first a construction of great strength relative to its weight, and in which the metal is used to enable the walls to be constructed of 20 minimum thickness, and provided with a cover which not only serves the usual purpose but also affords a reinforced interior shoulder or brace adapted to resist the crushing inward of the side walls, due to the pressure 25 of the earth against the same.

It is also an object of the invention to provide a construction in which the cover when in place is sealed and locked by reinforcing connections to afford in fact a unitary construction of the vault and cover.

It is also an object of the invention to afford in connection with the reinforcing means for the cover, centrally disposed loops or eyes whereby the cover may be handled 15 and to provide at the top of the box or case an increased thickness permitting a longitudinal groove or channel to be formed therein to receive the reinforcement of the cover and to engage the same in place by suitable 40 cementing material.

It is finally an object of the invention to provide a burial vault or case impervious to moisture and air if desired, of the greatest possible strength and durability, with slight 45 weight and at a price sufficiently cheap to warrant the general introduction and use of the same.

The invention consists in the matters hereinafter defined and more fully pointed 50 out in the appended claims.

As shown in the drawings: Figure 1 is a central longitudinal section of a device embodying my invention. Fig. 2 is a transverse section thereof. Fig. 3 is a perspective view partly in section to illustrate the reinforcing metallic skeleton

In said drawings: The box or case shown is rectangular and monolithic consisting of molded concrete, and comprises a bottom A, side walls a and end walls a', embedded in which is a reinforcing skeleton of steel bars or rods which as shown in Fig. 3 comprises first a bar B rectangular in cross section which is bent to extend entirely around the bottom near the outer wall affording a reinforcement both for the sides and ends of the bottom. Intermediate the side bars B are longitudinal bars B' similar thereto, the ends of which are bent upwardly around the end bars b to form the reinforcing vertical 70 end bars b'. Any desired number of said intermediate bars may of course be employed. Transverse bars B² are provided in any desired number the ends of which outside the side bars B, are bent upwardly 75 to afford the side reinforcing bars b² which correspond with the end bars b'. These extend to near the top of the box. Said bottom, side and end walls are relatively thin and said side and end walls at their top are 80 increased in thickness outwardly to afford a groove extending in the top thereof downwardly, or, if preferred a succession of sockets, and as shown the portion of the side and end walls thus built and extended outwardly beyond said groove or sockets is reinforced by a bar or rod B³ which extends around the sides and ends of the case on the outer side of said end and side bars b'-b². The cover C is also of relatively thin molded 85 concrete reinforced by rods or bars similar to those before described. Said cover as shown is arched upwardly both longitudinally and transversely and is shaped at its ends and edges to rest flat upon the side and 90 end walls of the case and to afford a shoulder c which fits within the side and end walls 95 bracing the same against inward crushing pressure.

As shown a reinforcing bar or rod D is 100 bent to afford the reinforcement for the side and end shoulders c and as shown is embedded in said shoulder below the top of the box. Extending also, longitudinally of the cover are reinforcing bars D' and D² of 105 which bar D² is located at or near the longitudinal center of the cover and the bars D' between the same and the edges of the cover. The bar D² as shown is embedded in said cover for its entire length 110 with the exception of its extremities, which are bent downwardly through the flat por-

tion of the margins of the cover and extend into the groove or the sockets in the end walls. The longitudinal bars or rods D' are bent downwardly at their ends and 5 bear against the end bars d in the end shoulders of the cover. Transverse reinforcing bars D³—D⁴ are provided in any desired number in said cover as shown extending over the bars D' and D² and arched to cover 10 form to the shape of the cover. The bars D³ extend over the bars D'—D² and at their extremities also protrude through the flat margin of the cover to engage in said groove or said sockets.

15 Intermediate the bars D³ and also near each end of the cover the bars D⁴ extend over the bars D' and D² as before described and the ends thereof are directed downwardly to abut against the reinforcing bars D in the 20 shoulders of said cover in the same manner that the ends of the longitudinal bars D' or supplemental bars inserted for the purpose are bent downwardly at their ends and abut against the transverse portion d of 25 said reinforcing bar D thus greatly strengthening said shoulders and enabling the same to withstand enormous pressure.

As shown metallic loops or eyes E are secured on the central longitudinal bars D² 30 and project through the cover at convenient points therein to enable the cover to be handled by suitable tackle in placing the same and also loops or eyes E' are secured on the reinforcing bar B³ at each end 35 and project outwardly to enable the vault to be handled either before or after sealing the same.

The operation is obvious from the foregoing description. When the case or vault 40 is to be closed permanently as after the reception of the casket, the cover is lowered to place and liquid cement of any suitable kind is poured into the groove in the walls filling the same, and flowing around the 45 downturned ends of the reinforcing bars of the cover and also effectually sealing the cover for its entire length to the top of the case thus forming a burial case or vault and its cover, monolithic in character. Any 50 suitable impervious paint may be used on the inner or both the inner and the outer walls of the cover and the box to hermetically seal the casket within its vault. From the construction described, bodies so interred are preserved free from any destructive 55 agencies from the surrounding soil and from external moisture and that with the use of a burial case such as described the grave is effectually protected from desecration. Furthermore the construction is such 60 that ordinary earth pressures cannot crush the case, and vaults so constructed will protect the remains to remote future time.

Of course, any external embellishment or ornamentation may be used if desired, and 65 the reinforcing materials used may be somewhat varied. I therefore do not purpose limiting this application for patent otherwise than necessitated by the prior art as details of construction may be varied without departing from the principles of this invention.

I claim as my invention:

1. A burial case or vault comprising a monolithic concrete box and a concrete 75 cover, the cover having a flat marginal face to rest on the top of the box, an inner shoulder on the cover fitting closely around the inner side of the side and end walls of the box, a reinforcing bar of metal embedded in said shoulder and extending continuously around the sides and the ends of the cover, reinforcing bars or rods extending transversely and longitudinally of the cover, some of which bear against said reinforcing 85 marginal bar in said shoulder and reinforcing bars embedded in the concrete extending longitudinally and transversely of the bottom of the box and their ends extending upwardly in the walls of the box. 90

2. A burial case or vault comprising a monolithic box and a cover, the cover having a flat marginal face to rest on the top of the box, an inner shoulder on the cover fitting closely around the inner side of the 95 side and end walls of the box, a reinforcing bar of metal embedded in said shoulder and extending continuously around the sides and the ends of the cover, reinforcing bars or rods extending transversely and longitudinally of the cover, some of which bear against said reinforcing marginal bar in said shoulder and the ends of the remaining bars engaging in the walls of the box to lock the cover in place. 100

3. A burial case or vault comprising a monolithic concrete box having the walls at the top increased in thickness and provided with a groove, a reinforcing bar in the thickened top extending therearound outside of the groove, transverse and longitudinal reinforcing bars in the bottom of the box having the ends directed vertically extending into and reinforcing the walls of the box, a concrete cover and reinforcing bars therein having the extremities extending beyond the margins of the cover into the groove. 110

In testimony whereof I have hereunto subscribed my name in the presence of two 120 subscribing witnesses.

WILLIAM C. LAECHLE.
